UNITED STATES PATENT OFFICE.

GRANVILLE E. BRADSHAW, OF HERSHAM, WALTON-ON-THAMES, ENGLAND.

INTERNAL-COMBUSTION-ENGINE CYLINDER.

1,252,319.

Specification of Letters Patent.

Patented Jan. 1, 1918.

Application filed March 12, 1917. Serial No. 154,388.

To all whom it may concern:

Be it known that I, GRANVILLE EASTWOOD BRADSHAW, a subject of the King of Great Britain and Ireland, of A. B. C. Motor Works, Hersham, Walton-on-Thames, in the county of Surrey, England, have invented new and useful Improvements in Internal-Combustion-Engine Cylinders, of which the following is a specification.

10 My invention relates to the design or manufacture of internal combustion engine cylinders for use on petrol, oil, and gas engines, of all types, but particularly for aeronautical engines, motor car and motor cycle engines, light stationary engines, and the like, where it is desirable to cool the cylinders without the necessity of using water circulation.

Made according to my present invention, 20 the cylinders are very light, cheap to manufacture, and they secure the advantages obtained by the use of materials of high heat conductivity.

Formerly, cylinders have been made of 25 cast iron, and other materials with fins or gills made of sheet or cast copper, aluminum, and the like, fitted by suitable means to the outside, but such arrangements have the disadvantage of insufficient metallic contact between the cylinder walls and the gills, or the necessity of brazing or otherwise attaching these satisfactorily.

The best known form of air cooled cylinder is that in which the cylinder is made of 30 cast iron, with the cooling fins or gills cast around the outside, but this has the disadvantage that cast iron is a very poor conductor of heat, and a sufficient number of fins or gills to give the maximum amount of 40 cooling cannot be cast on the cylinder on account of the difficulties encountered in the manufacture of the casting and the necessity for comparatively thick fins or gills, in order to render casting easy.

45 In the drawing,

Figure 1 is a central vertical section through an engine cylinder having my invention embodied therein.

Fig. 2 is a sectional view taken at right angles to Fig. 1 taken between two adjacent ribs or fins.

In my invention I employ a cylinder A machined from a steel bar or tube, or other material of high heat conductivity, on the 55 outside of which are machined fins or gills

C of the correct size, shape and spacing to give the most effective cooling. Copper is then electrically deposited on the outside of the cylinder to form a layer B over both the cylinder and fins in order to assist in conducting the heat from the cylinder along the sides of the fins.

Copper is known to be one of the best materials for conducting heat, but any other metal that is a satisfactory heat conductor 60 may be used where it is possible to deposit same. Any such deposit may be applied either to individual cylinders or to cylinders assembled in a group.

The advantages obtained by my invention 70 are that the cylinders are cheap to manufacture, most scientifically correct spacing and shape of fins, etc., can be obtained, there is an excellent support for the copper when deposited, and a maximum amount of heat 75 can be dissipated by the fins owing to the conduction of heat by the layer B from the cylinder body to the tips of the fins.

I claim:

1. As an article of manufacture an engine cylinder having radiating fins integral therewith, said cylinder and fins having a strength, rigidity, and heat conductivity of the order of steel, and a continuous exposed layer of copper of substantially uniform 85 thickness adhering to the sides of said fins and the outer surface of said cylinder.

2. An engine cylinder provided with integral radiating fins, and an adherent coating of metal of high heat conductivity of substantially uniform thickness on the cylinder and fins whereby heat from the cylinder barrel is conducted toward the tips of the fins by said metal of high heat conductivity, thereby providing a cylinder of greater 95 radiation capacity than that obtained by one having fins made of the same material as the cylinder, and of greater strength than one having fins of high heat conducting metal only.

3. An engine cylinder having integral fins homogeneous therewith, said cylinder and fins being formed of a material having high strength and heat conductivity as compared with cast iron, and a coating of substantially uniform thickness of metal of high heat conductivity as compared with the heat conductivity of the body of the cylinder in adhesive contact in said cylinder and fins over substantially the entire surface there. 110

2
of, whereby greater radiation capacity of
the cylinder is obtained and also strength of
the cylinder as compared with cylinders
having separately attached fins.

5 4. An engine cylinder with integral fins,
said cylinder and fins being of homogeneous
steel to provide high strength and heat con-
ductivity, and a layer of copper of substan-
tially uniform thickness in adhesive contact
10 with said cylinder and fins over substantially
the entire surface thereof, whereby high
heat conductivity of the fins is obtained and
also whereby greater strength for the com-

bined cylinder and fins is obtained than
would be obtained with separate fins.

15

5. An engine cylinder having integral fins
homogeneous therewith, said cylinder and
fins being of a material of high strength
and heat conductivity as compared with cast
iron, and a layer of metal of substantially 20
uniform thickness and of high heat conduc-
tivity as compared with the body of the cy-
linder in adhesive contact with said cylinder
and fins over substantially the entire surface
thereof.

GRANVILLE E. BRADSHAW.
